Primary Examiner — Paul D Bohannon(74) *Attorney, Agent, or Firm* — Fitch, Even, Tabin & Flannery LLP(57) **CLAIM**

The ornamental design for a sofa, as shown and described.

DESCRIPTION

FIG. 1 is a front, top, left perspective view of a sofa, showing my new design;

FIG. 2 is a rear, top, right perspective view thereof;

FIG. 3 is a rear, bottom, left perspective view thereof;

FIG. 4 is a rear, top, left perspective view thereof;

FIG. 5 is a front, top, right perspective view thereof;

FIG. 6 is a front elevational view thereof;

FIG. 7 is a rear elevational view thereof;

FIG. 8 is a top plan view thereof;

FIG. 9 is a bottom plan view thereof;

FIG. 10 is a right side elevational view thereof, the left side elevational view being a mirror image; and,

FIG. 11 is an enlarged, cross-sectional view taken along line 11-11 in FIG. 6.
